UNITED STATES PATENT OFFICE.

ALLIE W. MARCY, OF PUTNAM, CONNECTICUT.

DESIGN FOR THE FINGER-GRIP PORTION OF A PIN-PUNCH OR SIMILAR TOOL.

57,139.

Specification for Design.

Patented Feb. 22, 1921.

Application filed November 10, 1920. Serial No. 423,189. Term of patent 14 years.

To all whom it may concern:

Be it known that I, ALLIE W. MARCY, a citizen of the United States of America, residing at Putnam, in the county of Windham and State of Connecticut, have invented a new, original, and ornamental Design for the Finger-Grip Portion of a Pin-Punch or Similar Tool, of which the following is a specification, reference being had to the accompanying drawing, forming a part thereof.

The figure is a plan view, for example of an extra long pin punch, showing my new design for the finger grip portion of a pin punch or similar tool.

I claim:

The ornamental design for the finger grip portion of a pin punch or similar tool, as shown.

ALLIE W. MARCY.
